UNITED STATES PATENT OFFICE.

ROBERT MORSE WITHYCOMBE, OF SYDNEY, NEW SOUTH WALES, AUSTRALIA.

MEANS FOR WITHDRAWING SMALL QUANTITIES OF MEDICAMENTS FROM RECEPTACLES OR CONTAINERS AND APPLYING THEM TO THE BODY.

Application filed September 28, 1926, Serial No. 138,224, and in Australia October 1, 1925.

This invention relates to improved means for withdrawing small quantities of medicaments from receptacles or containers and applying them to the body. My object has 5 been to avoid waste and spilling of the medicament and to facilitate its application to restricted areas, more particularly to dental cavities prior to filling or stopping, or to the investing tissue and adjacent parts.

10 The invention consists in springing on to one end of a rigid holder or stem, preferably a metal or vulcanite rod of small diameter, a tip of tubular resilient rubber in such a manner that a portion of the tube projects 15 a short distance beyond the end of the holder or stem and that the portion of the tube on the stem forms an air tight joint with the latter. The end of the stem may have 20 a portion of reduced diameter of a length approximately about half the length of the tubular rubber tip and said end may have one or more grooves or recesses to afford a better grip of the rubber and thus prevent it slipping off when in use.

25 In some cases I may form the projecting portion of the rubber tip with a swelling or extension forming a chamber to enable a larger quantity of the medicament to be taken up, and I may provide an additional 30 opening laterally in said portion of the tip. Preferably also I provide a rigid band or clip of suitable metal, vulcanite or hard rubber, or wood, which will fit tightly over that tubular portion of the tip on the reduced 35 end of the stem so as to prevent said tip slipping off when in use.

But in order that my invention may be more clearly comprehended I now refer to the accompanying drawing in which

40 Figure 1, is a perspective view (slightly enlarged) of a preferred shape of instrument according to this invention, and

45 Figure 2, an enlarged perspective view showing the reduced end of the holder or stem with its rubber tubular tip removed.

A holder or stem 3, knurled at 4 to afford

convenient grip for the operator's fingers, is turned down or reduced at 5 (see Figure 2) to form shoulder 6 against which tip 7 abuts. This tip 7 is of resilient tubular 50 rubber of a length approximately twice the length of the reduced end of the holder on which it is adapted to be firmly held when sprung thereon.

In use the end of holder or stem 3 with 55 its tip 7 thereon is dipped into the medicament and pressed firmly against a rigid part of the container so as to expel the air in the projecting portion of said tip 7. When said resilient tip 7 is permitted to regain its normal shape a small quantity of the medicament is drawn therein ready for application to a dental cavity or other part of the body.

It should be understood that the end of 65 holder or stem 3 need not necessarily be reduced although it is so illustrated as preferred, for such end may have a collar integral therewith or shrunk thereon or alternatively, such end may be knurled or have 70 grooves therein to provide a better grip for rubber tip 7.

I claim:

1. A device for withdrawing a small quantity of medicament from a receptacle and 75 applying it to the body, comprising a holder or stem having a portion of its length at one end of reduced cross-section to form an abutment or shoulder, and a resilient tip adapted to be removably sprung over, and to 80 project from the end of the reduced portion of said holder or stem.

2. A device for withdrawing a small quantity of medicament from a receptacle and 85 applying it to the body, comprising a stem and a resilient substantially tubular member removably sprung over said stem at one end of the latter and projecting beyond said end.

In testimony whereof I have hereunto set my hand.

ROBERT MORSE WITHYCOMBE.
